UNITED STATES PATENT OFFICE.

LOUIS H. ORSON, OF WILLOUGHBY, OHIO.

PAPER-PICKER.

1,234,794.

Specification of Letters Patent. Patented July 31, 1917.

Application filed November 6, 1915. Serial No. 60,005.

To all whom it may concern:

Be it known that I, LOUIS H. ORSON, a subject of the King of Great Britain, residing at Willoughby, in the county of Lake 5 and State of Ohio, have invented certain new and useful Improvements in Paper-Pickers; and I do hereby declare the following to be a full, clear, and exact description of the invention, such as will enable others 10 skilled in the art to which it appertains to make and use the same.

The invention relates to improvements in picking devices.

The object of the present invention is to 15 improve the construction of picking devices and to provide a simple, inexpensive and efficient paper picker of strong and durable construction designed for use in parks, places of amusement and the like for picking up 20 paper, orange peels, banana peels, candy boxes and the like and equipped with a spike or pointed rod on which such articles are collected and having means for expelling and discharging such articles where- 25 by the same may be conveniently deposited in a suitable receptacle.

A further object of the invention is to provide a paper picker of this character capable of being easily and quickly operated 30 so that a person may remove rubbish from a relatively large area in a comparatively small space of time and without bending or stooping.

With these and other objects in view the 35 invention consists in the construction and novel combination and arrangement of parts hereinafter fully described, illustrated in the accompanying drawings and pointed out in the claims hereto appended, it being under- 40 stood that various changes in the form, proportion and minor details of construction may be resorted to without departing from the spirit or sacrificing any of the advantages of the invention.

45 In the drawings—

Figure 1 is a side elevation of a paper picker constructed in accordance with this invention,

Fig. 2 is a longitudinal sectional view of 50 the same.

Like numerals of reference designate corresponding parts in the several figures of the drawing.

In the accompanying drawing in which is 55 illustrated the preferred embodiment of the invention, 1 designates a pointed rod spike

slidably mounted in a sleeve or tubular member 2 and movable inwardly and outwardly with respect to the same for arranging the pointed rod or spike in an extending projecting position for collecting paper, banana peels, orange peels and the like by spearing the same and for withdrawing the spike or rod from the collected material to deposit the latter in a suitable 60 receptacle. The tubular member 2 which is preferably in the form of a casting is provided at its outer end with projecting arms or wings 3 which form a stop for limiting the inward movement of the speared material on the rod or spike which is connected to one end of a coiled spring 4 for moving the spike in one direction with relation to the tubular member 2. The tubular member is secured at its inner end to 65 a relatively fixed handle 5 consisting of a wooden rod provided in its lower end with a socket or bore 6 into which the 70 slideable rod or spike 1 moves when the same is drawn inwardly by a sliding sleeve or 75 handle 7. The sliding sleeve or handle 7 which is arranged on the relatively fixed handle 5 is equipped with a transverse bolt 8 extending through longitudinal slots 9 formed in the relatively fixed handle and 80 in the sleeve and adapted to permit the slideable handle to move longitudinally of the device to permit the coiled spring to 85 actuate the slideable rod or spike 1. The 90 slideable sleeve is equipped with a catch consisting of a lever 10 fulcrumed at an intermediate point at 11 to provide inner and outer arms, the outer arm having an inwardly projecting engaging portion 12 adapted to extend into a recess 13 for locking the spike in an extended position and also for relieving the spring of strain incident to spearing a heavy piece of paper or the like. The spring is secured at its inner 95 end 14 to the tubular member and its outer end 15 which is connected with the rod or slideable member 1 operates in a slot 16 in the tubular member 2.

When the rod or member 1 is arranged in a projecting position it is adapted for spear- 105 ing the material to be collected and the catch is maintained in engagement with the notch 13 by a spring 17 and is operated to release the slideable sleeve or handle when it is desired to remove the accumulated trash 110 from the projecting portion of the slideable rod or member 1.

What is claimed is:—

1. A paper picker including a tubular member, a relatively fixed handle, connected with the tubular member, a rod having a 5 pointed end slidably mounted in said tubular member, a sliding operating sleeve carried by the tubular member, means rigidly connecting said sleeve and rod, said means being adapted to limit the sliding movement 10 of said rod.
2. A paper picker including a tubular member, a relatively fixed handle connected with the tubular member, said tubular member having a slideable rod therein, a slideable 15 sleeve carried by the tubular member and means for connecting the slideable sleeve and slideable rod, and means carried by the slideable sleeve and co-operating with the tubular member for locking the slideable rod in an 20 extended position.
3. A paper picker including a tubular member, a relatively fixed handle connected with the tubular member, a rod having a pointed lower end slidably mounted in said 25 tubular member, an operating handle slideably carried by said tubular member, and

means rigidly connecting the sliding operating handle and the upper end of the rod, said means limiting the sliding movement of the rod and preventing any relatively rotary movement of the rod and tubular member. 30

4. A paper picker including a tubular member, a relatively fixed handle connected with the tubular member, a rod slidably mounted in said tubular member, an operating sleeve slideably carried by said tubular member, means connecting said operating sleeve and rod, a spring having one end secured to said tubular member and the opposite end to said slideable rod to normally hold said rod in said tubular member, and a pivoted catch carried by said operating member for locking the slideable rod in an extended position. 35

In testimony whereof I affix my signature in presence of two witnesses.

LOUIS H. ORSON.
